UNITED STATES PATENT OFFICE.

MAURICE BERNAYS JOHNSON, OF SAN ANTONIO, TEXAS.

COMBINED WIRE AND WIRELESS TELEGRAPH SYSTEM.

996,089.

Specification of Letters Patent. Patented June 27, 1911.

Application filed October 6, 1910. Serial No. 585,543.

To all whom it may concern:

Be it known that I, MAURICE BERNAYS JOHNSON, a citizen of the United States, and a resident of San Antonio, in the county of 5 Bexar and State of Texas, have made and invented certain new and useful Improvements in Combined Wire and Wireless Telegraph Systems, of which the following is a specification.

10 My invention relates to combined wire and wireless telegraph systems, and the object thereof is to provide a telegraph system in which an ordinary wire transmission line is used for a part of the distance to be traversed, after which the message is transferred to and sent through space as in wireless systems, the wireless transmission mechanism being under the control of the operator at the end of the wireless circuit remote there- 15

20 from.

There will preferably be a wire transmission line leading from each end of the wireless transmission system, so that an operator may transmit a message through a wire system for any distance, transfer to a wireless system, and then continue communication through a second wire circuit, the wireless system in such case being a connecting link between two wire circuits, the nearer ends 25 of which may not readily be connected by wires.

With the above objects in view, my invention consists in the combined wire and wireless telegraph system illustrated in the accompanying drawing, described in the following specification, and particularly claimed in the clauses of the concluding claim, and in such modifications thereof as will be obvious to one skilled in the art to which my in- 30

40 vention relates.

In the drawing, the view shows in diagram the preferred form of my invention.

The upper portion of the view shows the termination of a wire circuit of any length 45 and the wireless station under the control of the operator at the remote end of the wire circuit, this wireless station being referred to as the sending station, while the lower portion of the view shows the receiving 50 wireless station and the wire circuit leading therefrom to any remote place, it being understood that the message is transmitted through space between the two wireless stations, and that there are no operators at 55 either wireless station, the operator at the remote end of the upper wire circuit com-

municating directly with the operator at the remote end of the lower wire circuit through the wireless system.

1, 2 are the ends of a wire circuit, the 60 other end of which may be any distance away.

3 is a telegraph relay adapted to control a normally open circuit 4 which includes a battery or other source of electricity 5 and 65 the primary of an induction coil 6, the secondary of which induction coil discharges through a spark gap 7 thus establishing an oscillatory flow through the circuit 8, coil 9, and condenser 10, and resulting in electrical 70 waves being sent out from the aerial wires 11 which are connected with the coil 9 through a sliding connection at 12, this apparatus being such as is commonly used in wireless telegraph apparatus. 75

13 is a circuit connected in shunt with the circuit 4, and which circuit includes a relay 14, which relay, when energized, establishes electrical communication between the aerial wire 11 and the sending portion of the wireless system of which it forms a part, communication between the coil 9 and aerial wire 11 being normally interrupted at 15. 80

16 is a circuit connected in series with the line wires 1, 2 and relay 3 and which is normally closed so that current may flow through the line wires 1, 2, relay 3 and circuit 16, but which circuit may be opened when a message is to be sent to the operator at the far end of the line 1, 2, to which end the circuit 16 includes a suitable circuit breaking device shown as in the form of a relay 17 so arranged that the circuit which it controls, that is the circuit 16, is normally closed. 85

90 The mechanism thus far described enables an operator at the far end of the wire line 1, 2 to send out electrical waves from the aerial 11; and the message thus sent is received at the distant wireless receiving station and transmitted over a wire line to a more distant receiving operator by mechanism as follows: 18 is the aerial at the receiving station, the same being normally in electrical 100 connection with the receiving elements of the second wireless station. 19 is a coherer included in a circuit 20 which establishes communication between the aerial 18 and the ground. 21 is a circuit in shunt with the coherer 19 and which circuit includes a battery 22 and a relay 23 which controls a normally open circuit 24 having a de-coherer 105 110

25 and batteries 26 therein, and which circuit 24 also includes a relay 27 controlling a normally open circuit 28, through which current may flow from the line wires 30, 31 5 when such circuit is closed.

In order that the current flowing in the circuit 28 shall flow through the line 30, 31 and not through the relay 32, which corresponds with the relay 3 in construction and 10 function, a relay 33 corresponding with the relay 17 and so arranged that the circuit 34, corresponding with the circuit 16, which it controls is normally closed, is connected in series in the circuit 28 which relay, upon being energized, breaks the circuit 34 and prevents current from the line wires 30, 31 and the line batteries from flowing in shunt through the relay 32, which, if permitted, would obviously result in that signals received by the aerial 18 would be sent out again over the same aerial as well as over the line 30, 31, thus interfering with the receiving function of the station.

In sending from the distant end of the line 25 1, 2 current flows through the relay 3 and circuit 16, the circuit 4 being made as the relay 3 is energized, whereby electrical waves are sent out from the aerial 11 by reason of the induction coil 6, spark gap 7, and condenser 10, it being remembered that the aerial 11 is connected with the sending elements of the wireless station by means of the relay 14 in the shunt circuit 13. The waves thus generated pass to the aerial 18, and the 30 relay 23 is energized by the battery 22, a flow being established by reason of the coherer 19 in the manner common in such devices. The relay 23 closes the circuit 24, thus energizing the relay 27 and closing the circuit 28, thus 35 sending a message over the line 30, 31 to a distant operator, the relay 32 being cut out by means of the relay 33 acting to break the circuit 34 as above explained, it being understood that the current for sending over the line 30, 31 is derived from the batteries of 40 other source of electricity commonly provided for such wire transmission systems.

I have described the operation of my system when used to transmit a message from 50 the remote end of the line 1, 2 through the wireless stations to the remote end of the line 30, 31. It will be understood, however, that a message may be sent in a reverse direction, each wireless station being equipped 55 with both sending and receiving apparatus, and, without specifically tracing a message from the remote end of the line 30, 31 to the remote end of the line 1, 2, it may be remembered that the relay 32 controls a circuit 35 60 corresponding in function with the circuit 4, and that 36 is a battery in such circuit which includes also the primary of an induction coil 37, 38 is a spark gap, 39 is a circuit including the secondary of the induction coil 37, 40 is a coil in such circuit,

and 41 a condenser, these elements being like in function to the corresponding elements 6, 7, 8, 9, 10 above referred to.

42 is a circuit corresponding with the circuit 13, and 43 is a relay included therein 70 for placing the aerial 18 in condition to send electrical impulses, the connection between the sending elements of the station and the aerial 18 being normally broken at 44.

45 is an adjustable or sliding contact between the coil 40 and the aerial for adjusting the frequency of vibration of the impulses sent out therefrom. Impulses sent from the aerial 18 are received by the aerial 11, as above explained for transmission in a reverse direction, 46 being a circuit including a coherer 47, 48 a circuit controlled by said coherer, 49 a battery and 50 a relay both included in said circuit.

51 is a circuit controlled by the relay 50 and which includes a de-coherer 52, batteries 53 and a relay 54, these elements being like in function and construction the elements 20, 19 and 21 to 27 above referred to. The relay 54 controls a circuit 55 like the circuit 28, and the relay 17 above referred to and the function of which is the same as the relay 33 as above explained is connected in series in the circuit 55.

The receiving instruments of each wireless station are inclosed by a screen formed preferably from woven wire, a portion of which is shown at 57, which screen is connected with the ground so that a high tension charge of electricity may not accumulate 100 upon the receiving instruments.

Having thus described my invention and explained the operation thereof, I claim and desire to secure by Letters Patent:

1. In a system of the type described, a relay; a circuit breaking device in operative relation with said relay and adapted to interrupt the flow of current through the magnet coil thereof; wireless sending instruments controlled by said relay; other wireless sending instruments located at a distance from said first mentioned sending instruments; and means controlled from said distant sending instruments for operating said circuit breaking device.

2. In a system of the type described, a relay; a circuit breaking device adapted to interrupt the flow of current through the magnet coil thereof and including an electromagnet the armature of which controls a 120 normally closed circuit in series with the magnet coil of said relay; wireless sending instruments controlled by said relay; other wireless sending instruments located at a distance from said first mentioned sending 125 instruments; a second relay controlled from said distant sending instruments; and a circuit controlled by said second relay and which circuit includes the magnet of said circuit breaking device and through which 130

current may flow to operate said circuit breaking device.

3. In a system of the type described, wireless sending instruments; wireless receiving instruments; other wireless sending instruments located at a distance from said first mentioned sending and receiving instruments; and means controlled from said distant sending instruments for rendering said 10 first mentioned sending instruments inoperative to send a message.

4. In a system of the type described, wireless sending instruments including a circuit breaking device; wireless receiving instruments; other wireless sending instruments located at a distance from said first mentioned sending and receiving instruments; and means controlled from said distant sending instruments for operating said 20 circuit breaking device.

5. In a system of the type described, a relay; a circuit breaking device adapted to interrupt the flow of current through the magnet coil thereof and including an electro- 25 magnet the armature of which controls a normally closed circuit in series with the magnet coil of said relay; wireless sending instruments controlled by said relay; wireless receiving instruments including a second 30 relay; other wireless sending instruments located at a distance from said first mentioned sending and receiving instru-

ments; and a circuit controlled by said second relay and which circuit includes the magnet of said circuit breaking device and through 35 which current may flow to operate said circuit breaking device.

6. In a system of the type described, a relay; a normally open circuit controlled by said relay; wireless sending instruments 40 controlled by said relay, the same including an aerial normally disconnected from said sending instruments; a second relay controlled by said first mentioned relay and adapted to connect said aerial with said 45 sending instruments; and wireless receiving instruments with which said aerial is normally connected.

7. In a system of the type described, two wireless stations located at a distance from 50 one another and each having wireless sending and receiving instruments; and means at each station whereby the sending instruments thereof may be rendered inoperative from the other station.

Signed at New York, borough of Manhattan, in the county of New York and State of New York, this 30th day of September, A. D. 1910.

MAURICE BERNAYS JOHNSON.
